REFRIGERATING APPARATUS

Lawrence A. Philipp, Detroit, Mich., assignor to Nash-Kelvinator Corporation, Detroit, Mich., a corporation of Maryland

Application February 24, 1939, Serial No. 258,162

8 Claims. (Cl. 230—206)

This invention relates to refrigerating apparatus and more particularly compressors for use in connection with such apparatus.

The invention consists in delivering the low pressure refrigerant from the evaporator to a chamber wherein the oil will be separated from the gaseous vapor by contacting with the walls of the chamber and also by gravity due to the greatly reduced velocity of the vapors upon entering the chamber. This oil which has been separated is conducted either by aspirating or metering means to the suction inlet of the compressor cylinder during the operation of the compressor and the oil, upon entering the cylinder, will seal the piston at the cylinder wall and prevent a dry knock; sealing the gas within the cylinder and prevent gas leakage; lubricating the piston and cylinder wall surfaces and thereby quieting the compressor and increasing its efficiency.

The invention consists of certain novel features of construction and combinations of parts which will be hereinafter described and pointed out in the claims.

In the accompanying drawings:

Fig. 1 is a view in elevation of a motor compressor unit with parts broken away and parts shown in section, and showing the invention applied in a schematic arrangement of a refrigeration system;

Fig. 2 is a view taken along line 2—2 of Fig. 1;

Fig. 3 is a fragmentary view in cross section of a similar type compressor with a modified arrangement of the invention;

Fig. 4 is a vertical view in cross section of another type of refrigerant compressor illustrating the adaptability of the invention thereto with modifications, and a schematic arrangement of a refrigerating system.

Referring to Figure 1 of the drawings, the dome shaped shell or casing 10 is provided with an end or cover plate 11 which is secured thereto by weld, or the like, for forming a hermetically sealed chamber for a motor compressor unit. Mounted within the casing or shell 10 is a suitable electrically operated motor 12 to which is operatively connected for driving a shaft 16. An annular member 17 is supported within the shell and serves as a support and housing for the motor. Depending from this annular member 17 is a casting forming a crank-case portion 20 and pump cylinder 21. The drive shaft 16 extends through the crank-case portion 20 and is journaled in bearings 18 and 19 therein. An eccentric 22 is fixed upon the shaft 16 and located within the crankcase.

Mounted upon the eccentric is a connecting rod 23 of the piston 24, so that upon the rotation of the shaft, the piston 24 will be reciprocated within the compressor cylinder 21. A cylinder head 25 is mounted on the cylinder, and interposed between

the cylinder head and cylinder is a valve plate 26. The cylinder head 25 is provided with a recessed intake chamber 27 into which the low pressure gaseous refrigerant is delivered through a pipe 28 which has open communication with the upper portion of the chamber 30 formed within the casting 10.

The low pressure refrigerant is delivered through a port 31 formed in the valve plate 26 and under the control of a reed type suction valve 32 carried by the plate. The compressed refrigerant is delivered from the cylinder 21 through a port 33, formed in the valve plate 26, and controlled by valve 34 extending into a recessed chamber 35 formed in the cylinder head 25 for the discharge of compressed refrigerant. The compressed refrigerant is conducted from the chamber 35 through conduit 37 into a muffler 38 and through conduits 38 and 39 to a condenser 40. The conduits 38 and 39 are connected together by means of a coupling 60 carried on the shell 10. The refrigerant as it passes through the condenser is liquified and delivered to the evaporator 44 by tube 43, of small diameter, from the condenser. The low pressure or heat laden refrigerant is conducted from the evaporator by conduit 45 to the motor compressor unit.

A coupling 46 secured to shell 10 connects conduit 45 with a tube 47 within the chamber 30. The end of the tube 47 terminates at a point below the lubricant level line 48 as maintained in chamber 30, the refrigerant being discharged directly into the body of lubricant. The tube 47 is provided with an opening (not shown) whereby a portion of the returning refrigerant is discharged directly into chamber 30 above the lubricant level 48.

Formed in the cylinder head 25 is a passage 51 that leads into the intake chamber 27. Projecting into passage 51 and positioned therein by sleeve 52 is a tube 53 of very small diameter whose opposite open end is submerged in the body of lubricant carried in chamber 30. The tube 53 serves to conduct a limited amount of lubricant from the reservoir into passage 51 and 27 to be drawn with the refrigerant through port 31 into the cylinder during the suction stroke of the piston 24. The tube 51 is of such a size as to meter sufficient lubricant with each charge of refrigerant into the compression chamber to eliminate dry knocking caused when sufficient lubricant cannot reach the head of the piston. Supplying lubricant into the top of the cylinder further serves to seal the piston with the cylinder wall and consequently seals the refrigerant from leakage past the piston, providing for greater efficiency of the compressor while at the same time quieting its operation.

In the modified form shown in Figure 3 there is provided a pumping arrangement for forcing

lubricant from a reservoir through opening 66 towards the bearing 68 by a pump comprising of a slot 70 arranged in the end of stud 72 embedded in the end of shaft 16. The lubricant will 5 be carried up the length of bearing 68, partially assisted by a spiral groove 74 formed on the bearing surface, into the crankcase 16. As the crankcase is sealed from chamber 30 except for passageway 18 the displaced gas within the crank- 10 case, on the compression stroke, will seek this outlet to escape into chamber 30. As the passageway 18 communicates at a point below the lubricant level 80 normally maintained in the crankcase the gas will force lubricant ahead of 15 itself through the passage 18 towards its outlet into the trough 82 wherein the lubricant will be dropped and trapped against flowing back into the crankcase. A passage 84 communicates from the trough 82 to the upper bearing 86 of the 20 shaft for supplying lubricant thereto. A second trough or well 88 is formed above cylinder 21 and below trough 82 to catch the overflow therefrom flowing over the lip 90. Lying in the trough 88 is a tube 92 of very small diameter 25 which leads to and forms communication with a passage 94 formed by cutting away gasket 96 between the plate 26 and the cylinder head 25 of the compressor. The passage 94 communicates with the intake chamber 27.

30 During the cycling of the compressor the lubricant overflows from the first trough 82 into the second trough 88 to be metered by its passage through the tube 92 into passage 94 and drawn with the refrigerant through the intake 35 chamber 27 into the compression chamber. It will be noted that the lubricant is not drawn into the cylinder from a reservoir solely by the suction force created by the reciprocating piston, but that there is provided a gravity flow from 40 a trough that is forcibly fed during the cycling of the compressor.

In Figure 4, still another form of the invention is illustrated, wherein the compressor, comprising in general, an outer casing 100 which includes a crankcase portion 102, adapted to contain a quantity of lubricating oil, and a cylinder block portion 104. A valve plate 106 and cylinder head 107 are clamped to the cylinder block 104 by means of bolts 108. Mounted within the 50 cylinder is a piston 110 which is adapted to be reciprocated therein by means of a connecting rod 112 pivotally connected to the piston and mounted upon a crank 114 of the crank shaft 116 journalled in the crankcase portion 102.

55 The compressor 100 is provided with a chamber or reservoir 118 formed in the wall thereof, and preferably located adjacent the cylinder block 110, into which the low pressure gaseous refrigerant is delivered from the evaporator of the refrigerating system. The chamber 118 has communication by means of a passage 120 formed at one end thereof with a recessed chamber 122 formed in the cylinder head 107. A duct 124 is formed in the valve plate 106 for establishing 60 communication between the chamber 108 and the chamber 122. An intake port 126 is formed in the valve plate 106 and normally closed by a check valve 128 for controlling the supply of gaseous refrigerant to the cylinder 104. The 65 cylinder 104 has communication with the discharge chamber 109 formed in the cylinder head 107 by means of a duct 108 formed in the plate 106. This duct or port 108 is normally closed by a valve 110 but is actuated upon the compression of the refrigerant in the cylinder 104

73 for delivering the compressed refrigerant into the chamber 108. The compressed refrigerant is discharged from the chamber 108 by a conduit 112 to a condenser 114 wherein the compressed refrigerant is liquified and is then conducted by conduit 116 to a receiver 118. The refrigerant is delivered from the receiver 118 by conduit 120 to an evaporator 122 and the vapor or gaseous refrigerant is delivered from the evaporator 122 by conduit 124 to the chamber 118 10 of the compressor. The chamber is of a size sufficient to permit the gaseous refrigerant upon entering the chamber, to expand and thereby lose some of its velocity and thereby permitting the lubricant contained in the refrigerant to become separated therefrom, while some of the lubricant will contact with the walls of the chamber and be separated from the refrigerant. This separated lubricant will collect on the bottom 20 of the chamber 118, and an opening 130 is provided in the wall of the chamber for allowing any excess lubricant to flow into the crankcase 102 of the compressor.

The passage 120 of the chamber is preferably 25 provided with a thimble 132 which is open at both ends, with the opening at the end entering the chamber 118 of smaller diameter than the portion extending into the passage 120. An aspirator tube 134 of small diameter, is mounted 30 within the chamber having one end thereof extending into the well 136 formed at the bottom of the chamber for the lubricant and the opposite end of the tube projecting into the thimble 132 of the passage 120. As the piston is moved 35 on its suction stroke, the low pressure or gaseous refrigerant will be drawn from the chamber 118 through the thimble 132, passage 124, and into the chamber 122 of the cylinder head and through the port or duct 126 into the cylinder 104. As 40 this refrigerant is drawn from the chamber 118 by the suction of the compressor, a certain amount of oil will be drawn through the tube 134 into the thimble 132 where the oil and gaseous refrigerant will commingle and be conducted 45 through passage 120 to the cylinder. The tube along with the flow of the gas through the thimble, functions as an aspirator, whereby a metered or small quantity of oil will be carried in suspension in the gaseous refrigerant to the cylinder 50 for sealing the piston within the cylinder and furnishing sufficient lubricant for the walls of the piston and cylinder to eliminate dry knocking that might be created by the delivery of the gaseous vapors to the cylinder.

55 From the foregoing, it will be apparent that the low pressure refrigerant is delivered, in the constructions shown, into chambers wherein a separation of lubricant and refrigerant may take place, and the lubricant collected, and a small 60 quantity of the lubricant is conducted or metered to the cylinder for the elimination of dry knock and permitting of greater efficiency of the compressor. By submerging the end of tube 51 deep into the reservoir as shown in Figure 1, or 65 providing the troughs or wells as shown in Figures 3 and 4, the lubricant is collected without any foam and only the pure lubricant is supplied to the cylinders along with the gaseous refrigerant to be compressed.

70 Although only a preferred form of the invention has been illustrated, and that form described in detail, it will be apparent to those skilled in the art that various modifications may be made therein without departing from the 75

spirit of the invention or from the scope of the appended claims.

I claim:

1. In a refrigerating apparatus comprising a compressor having a cylinder and a piston, said cylinder having an intake chamber for gaseous refrigerant, a separating chamber located adjacent the cylinder and communicating with said intake chamber, by a passage, means for delivering low pressure gaseous refrigerant containing lubricant to said separating chamber for separating the lubricant therefrom, a reservoir in said separating chamber for receiving the separated lubricant, a metering tube for conducting a small quantity of lubricant from said reservoir to said passage, said separated refrigerant being conducted through said passage to the intake chamber during the operation of the compressor and causing the lubricant to be drawn from the reservoir through the tube and into the passage therewith. 15
2. In a refrigerating apparatus comprising a compressor having a compression chamber and an intake port for said compression chamber, a separating chamber, means for conducting low pressure refrigerant and entrained lubricant to said separating chamber, a reservoir associated with said separating chamber for receiving separated lubricant, a passageway for conducting the low pressure refrigerant from said separating chamber to said intake port and a conduit having its one end disposed in said reservoir below the level of lubricant therein and its other end communicating with the said intake port, said conduit having a restricted metering passageway for conducting measured quantities of lubricant from said reservoir to said intake port. 20
3. In a refrigerating apparatus comprising a compressor having a compression chamber and an intake port for said compression chamber, a separating chamber, means for conducting low pressure refrigerant and entrained lubricant to said separating chamber, a reservoir associated with said separating chamber for receiving separated lubricant, a passageway for conducting the low pressure refrigerant from said separating chamber to said intake port and a continuous conduit having its one end disposed in said reservoir below the level of lubricant therein and its other end communicating with the said intake port, said conduit having a restricted metering passageway for conducting measured quantities of lubricant from said reservoir to said intake port. 25
4. In a refrigerating apparatus comprising a compressor having a compression chamber and an intake port for said compression chamber, a separating chamber, means for conducting low pressure refrigerant and entrained lubricant to said separating chamber, a well associated with said separating chamber for receiving separated lubricant, said well being disposed above said intake port, a passageway for conducting the low pressure refrigerant from said separating chamber to said intake port and a horizontally disposed metering passage having its one end opening into said well and its other end communicating with said intake port for conducting measured quantities of lubricant from said well to said intake port. 30
5. In a refrigerating apparatus comprising a compressor having a compression chamber and an intake port for said compression chamber, a separating chamber, means for conducting low pressure refrigerant and entrained lubricant to said separating chamber, a well associated with said separating chamber for receiving separated lubricant, said well being disposed above said intake port, a passageway for conducting the low pressure refrigerant from said separating chamber to said intake port and a horizontally disposed metering passage having its one end opening into said well and its other end communicating with said intake port for conducting measured quantities of lubricant from said well to said intake port. 35
6. In a refrigerating apparatus comprising a compressor having a compression chamber and an intake port for said compression chamber, a separating chamber, means for conducting low pressure refrigerant and entrained lubricant to said separating chamber, a well associated with said separating chamber for receiving separated lubricant, said well being disposed above said intake port, a passageway for conducting the low pressure refrigerant from said separating chamber to said intake port and a horizontally disposed metering passage having its one end opening into said well and its other end communicating with said intake port for conducting measured quantities of lubricant from said well to said intake port. 40
7. In a refrigerating apparatus comprising a compressor having a compression chamber and an intake port for said compression chamber, a separating chamber, means for conducting low pressure refrigerant and entrained lubricant to said separating chamber, a well associated with said separating chamber for receiving separated lubricant, a conduit extending vertically to the upper portion of said separating chamber for conducting the low pressure refrigerant from said upper portion of said separating chamber to said intake port and a second conduit having its one end disposed in said well below the level of lubricant therein and its other end communicating with said intake port, said second conduit forming a restricted metering means for conducting measured quantities of lubricant from said well into said compression chamber through said intake port during the passage of low pressure refrigerant through said intake port to said compression chamber. 45
8. In a refrigerating apparatus comprising a compressor having a cylinder and a piston, said cylinder having an intake and exhaust port, said cylinder affixed to and opening into an enclosed crankcase, a crankshaft journaled in said crankcase and operatively connected to said piston, a chamber adjacent said compressor, a means for moving lubricant from said chamber into said crankcase, a trough in said chamber positioned at a height above said intake port, a passageway communicating from said crankcase with said trough in manner to allow the displaced air from said crankcase to carry lubricant therefrom to said trough, a communicating passage between said trough and said intake port, and means interposed in said communicating passage to measure the quantity of lubricant to be admitted with each charge of refrigerant into said cylinder. 50
9. In a refrigerating apparatus comprising a compressor having a cylinder and a piston, said cylinder having an intake and exhaust port, said cylinder affixed to and opening into an enclosed crankcase, a crankshaft journaled in said crankcase and operatively connected to said piston, a chamber adjacent said compressor, a means for moving lubricant from said chamber into said crankcase, a trough in said chamber positioned at a height above said intake port, a passageway communicating from said crankcase with said trough in manner to allow the displaced air from said crankcase to carry lubricant therefrom to said trough, a communicating passage between said trough and said intake port, and means interposed in said communicating passage to measure the quantity of lubricant to be admitted with each charge of refrigerant into said cylinder. 55
10. In a refrigerating apparatus comprising a compressor having a cylinder and a piston, said cylinder having an intake and exhaust port, said cylinder affixed to and opening into an enclosed crankcase, a crankshaft journaled in said crankcase and operatively connected to said piston, a chamber adjacent said compressor, a means for moving lubricant from said chamber into said crankcase, a trough in said chamber positioned at a height above said intake port, a passageway communicating from said crankcase with said trough in manner to allow the displaced air from said crankcase to carry lubricant therefrom to said trough, a communicating passage between said trough and said intake port, and means interposed in said communicating passage to measure the quantity of lubricant to be admitted with each charge of refrigerant into said cylinder. 60
11. In a refrigerating apparatus comprising a compressor having a cylinder and a piston, said cylinder having an intake and exhaust port, said cylinder affixed to and opening into an enclosed crankcase, a crankshaft journaled in said crankcase and operatively connected to said piston, a chamber adjacent said compressor, a means for moving lubricant from said chamber into said crankcase, a trough in said chamber positioned at a height above said intake port, a passageway communicating from said crankcase with said trough in manner to allow the displaced air from said crankcase to carry lubricant therefrom to said trough, a communicating passage between said trough and said intake port, and means interposed in said communicating passage to measure the quantity of lubricant to be admitted with each charge of refrigerant into said cylinder. 65
12. In a refrigerating apparatus comprising a compressor having a cylinder and a piston, said cylinder having an intake and exhaust port, said cylinder affixed to and opening into an enclosed crankcase, a crankshaft journaled in said crankcase and operatively connected to said piston, a chamber adjacent said compressor, a means for moving lubricant from said chamber into said crankcase, a trough in said chamber positioned at a height above said intake port, a passageway communicating from said crankcase with said trough in manner to allow the displaced air from said crankcase to carry lubricant therefrom to said trough, a communicating passage between said trough and said intake port, and means interposed in said communicating passage to measure the quantity of lubricant to be admitted with each charge of refrigerant into said cylinder. 70
